UNITED STATES PATENT OFFICE.

JOHN DI GAUDIO, OF BROOKLYN, NEW YORK, ASSIGNOR TO MODERN LIGHTING FIXTURE CO., INC., A CORPORATION OF NEW YORK.

DESIGN FOR A LIGHTING-FIXTURE BRACE OR ARTICLE OF ANALOGOUS NATURE.

Application filed April 30, 1929. Serial No. 31,056. Term of patent 3½ years.

To all whom it may concern:

Be it known that I, JOHN DI GAUDIO, a citizen of the United States of America, and a resident of Brooklyn, county of Kings, and State of New York, have invented a new, original, and ornamental Design for a Lighting-Fixture Brace or Article of Analogous Nature, of which the following is a specification, reference being had to the accompanying drawing, forming a part hereof.

In the drawing:

Figure 1 is a side elevational view of the lighting fixture brace or article of analogous nature;

Figure 2 is a face view of the same; and

Figure 3 is a central sectional view of the same.

I claim:

The ornamental design for a lighting fixture brace or article of analogous nature substantially as shown.

JOHN DI GAUDIO.
